CUTTING IMPLEMENT

Hobart A. McDaniel, Anderson, Ind.

Application October 25, 1946, Serial No. 705,690

1 Claim. (Cl. 30—318)

1

This invention relates to an agricultural, garden, etc., device.

The chief object of this invention is to provide a flexible or resilient bladed cutter of handled type whereby tall grass, weeds, shrubs, and small trees, etc., may be cut and hedges, bushes, and trees may be trimmed.

The chief feature of the present invention resides in applying in endwise relation to an elongated light-weight handle a curved, tempered spring steel strip sharpened at opposite sides and the free end, if desired, which strip is of very thin gauge so that in use little or no jar is transmitted to the hand or arm.

One feature of the invention resides in the use of the device for the cutting of tall grass or weeds in much the same manner as one puts with one hand in golf. The blade despite its curvature, cuts a relatively wide swath.

Another feature noted is that the round or blunt point can be used as a weed digger.

Still a further feature noted is that for bushes and heavy stalks, and very small trees, the invention is used as a driver is used in golf, all without appreciable shock.

Other objects and features of the invention will be set forth more fully hereinafter.

The full nature of the invention will be understood from the accompanying drawings and the following description and claim:

In the drawings Fig. 1 is a perspective view of one embodiment of the invention, the major portion of the handle being broken away.

Fig. 2 is an enlarged longitudinal sectional view of the blade and handle at the connection therebetween, the handle notch and blade thickness being approximately twice actual thickness and handle thickness being approximately to scale, the section being taken on line 2—2 of Fig. 1 and in the direction of the arrows.

Fig. 3 is an enlarged transverse sectional view of the blade, same being taken on line 3—3 of Fig. 1 and in the direction of the arrows.

Fig. 4 is a plan view of the free end of the blade shown in Fig. 1.

Fig. 5 is a similar view of a modified form of blade end.

In Figs. 1 to 4 of the drawings there is illustrated one embodiment of the invention. 10 indicates an elongated wood handle which at one end is notched or kerfed as at 11, same terminating as at 12.

Therein is seated the base or one end 13 of a strip of steel 14. This is of tempered spring

2

character and includes apertures 15 in longitudinal alignment.

The notched end of the handle has similarly aligned and spaced holes 16. Seated therein are 5 the carriage bolt type members having threaded shanks 17, the polygonal portions 18, the larger circular bearing portions 19 and the flat larger heads 20 with screw driver slots 21.

When same are seated in holes 16 of the handle 10 and apertures 15 of the blade and have washers 22 and nuts 23 applied thereto and tightened thereon, the portions 22 and 19 embed in the handle and blade is rigidly anchored thereto. The blade 14 projects longitudinally from the notched 15 end of said handle 10.

The blade is curved as indicated at 14 so that the free end 25 may be positioned approximately at right angles to base portions 13 thereof.

Each side edge of the blade 14 is sharpened 20 as indicated at 26 in Fig. 3 and the tip 25 is also sharpened as indicated at 27 in Fig. 4.

In Fig. 5 the blade tip 125, sharpened as at 27, is shown semi-circular in outline instead of substantially rectangular as in Figs. 1 and 4, 25 same having rounded corners 28.

The length and width of the blade is optional. Steel having 1.02% carbon and .70 manganese with a Rockwell test of C48½ has been found suitable. The strip is approximately .028 of an 30 inch thick and approximately one and a half inches wide. A strip of this tempered spring steel about 14 inches long curved to an approximate radius of about ten inches and anchored by $\frac{3}{16}$ " to $\frac{1}{4}$ " bolts as illustrated has been found 35 eminently satisfactory for all the purposes herein described including hedge, tree and shrubbery trimming as well as limb lopping.

The foregoing dimensions and specifications 40 are illustrative only. Such a blade can be readily curved or straightened as it is desired to depart from the transverse positioning recited.

In swath cutting the curved portion of the blade strikes the ground, and flattens the former, but due to the follow through cuts the grass, weeds, etc., ahead of the point of impact and due 45 to the impact cuts the swath specified.

While the invention has been illustrated and described in great detail in the drawings and foregoing description, the same is to be considered 50 as illustrative and not restrictive in character.

The several modifications described herein as well as others which will readily suggest themselves to persons skilled in this art, all are considered 55 to be within the broad scope of the in-

vention, reference being had to the appended claims.

The invention claimed is:

A cutting tool of the character described comprising an elongated handle having a slot formed in one end thereof, an elongated blade of resilient sheet metal extending from said handle, one end of said blade being accommodated within said slot, means rigidly securing said one end to the handle within said slot thereof, said blade being progressively curved in such manner that its free end normally lies in a plane approximately transverse to the plane of the handle, said blade having its side edges sharpened for cutting purposes, the free end of said blade be-

ing formed to define substantially a semi-circle wherein the edges of the semi-circle are sharpened for digging purposes.
